DESIGN FOR A LUBRICATOR CASING

Richard P. Field, Indian Hill, Ohio, assignor to
The Cincinnati Ball Crank Company, Cincinnati,
Ohio, a corporation of Ohio

Application March 28, 1938, Serial No. 76,135

Term of patent 7 years

To all whom it may concern:

Be it known that I, Richard P. Field, a citizen of the United States, residing at Indian Hill, in the county of Hamilton and State of Ohio, have invented a new, original, and ornamental Design for a Lubricator Casing, of which the following is a specification, reference being had to the accompanying drawing, forming a part thereof.

The figure of the drawing is a perspective view

of a lubricator casing showing my new design. The opposite side and rear surfaces of the casing have substantially the same appearance as the side and front portions shown.

I claim:

The ornamental design for a lubricator casing, substantially as shown and described.

RICHARD P. FIELD.
